UNITED STATES PATENT OFFICE.

LEO DUPAR, OF SAN FRANCISCO, CALIFORNIA.

DESIGN FOR A REVOLVING SIGN.

Application filed February 12, 1924. Serial No. 8,617. Term of patent 14 years.

To all whom it may concern:

Be it known that I, LEO DUPAR, a citizen of United States of America, residing at San Francisco, in the county of San Francisco and State of California, have invented a new, original, and ornamental Design for Revolving Signs, of which the following is a specification, reference being had to the accompanying drawings, forming a part hereof.

The figure is a perspective view showing my new, original and ornamental design for revolving signs.

I claim:—

The ornamental design for a revolving sign as shown.

LEO DUPAR.

Witnesses:

MABEL E. STANTON,
HAZEL A. WELCH.
